UNITED STATES PATENT OFFICE.

PHILIP GUY LLOYD, OF BALTIMORE, MARYLAND, ASSIGNOR TO CARR-LOWREY GLASS COMPANY, OF BALTIMORE, MARYLAND.

DESIGN FOR A JAR.

Application filed June 29, 1929. Serial No. 31,893. Term of patent 14 years.

To all whom it may concern:

Be it known that I, PHILIP G. LLOYD, a citizen of the United States, residing at Baltimore, in the county of Baltimore and State of Maryland, have invented a new, original, and ornamental Design for a Jar, of which the following is a specification, reference being had to the accompanying drawing, forming part thereof.

Figure 1 is an elevation of a jar showing my new design, there being illustrated only

a portion of the ornamentation that extends around the jar.

Figure 2 is a bottom plan view of the jar showing a segmental portion of the ornamentation.

Figure 3 is a fragmentary detail of the ornamentation.

I claim:

The ornamental design for a jar, as shown and described.

PHILIP GUY LLOYD.
